UNITED STATES PATENT OFFICE.

PAUL ELLIOTT CREWS, OF DURHAM, NORTH CAROLINA, ASSIGNOR TO GOLDEN BELT MANUFACTURING COMPANY, OF DURHAM, NORTH CAROLINA, A CORPORATION OF NEW JERSEY.

BAG-CLOSURE.

1,318,974.

Specification of Letters Patent.

Patented Oct. 14, 1919.

Application filed August 4, 1917. Serial No. 184,466.

To all whom it may concern:

Be it known that I, PAUL ELLIOTT CREWS, a citizen of the United States, residing at Durham, in the county of Durham and 5 State of North Carolina, have invented new and useful Improvements in Bag-Closures, of which the following is a specification.

The present invention relates to an improved bag closure and method of closing 10 and sealing bags, and is designed particularly for those bags of fibrous material now generally used for packing granulated tobacco, although it will be understood that the invention is not confined to this particular use, as it may be applied to any container formed of flexible material for carrying various commodities.

The invention is designed to provide a closure for and method of closing bags, 20 which will reduce the cost of closing and sealing the bags to a minimum; give a smooth, flat top to the bag; and provide a sealed top which when initially opened will present the contents of the package to the 25 consumer without the necessity of opening up the pull strings which are now commonly used.

In the drawings herewith I have illustrated the various steps in the formation of 30 this closure, and in said drawings:

Figure 1 is a view in perspective of a bag, the top of which is fully open and before any of the closing and sealing steps have taken place.

35 Fig. 2 is a perspective view of the top of a bag with the end folds of the closure made.

Fig. 3 is a perspective view of the bag, one of the side folds having been made.

Fig. 4 is a perspective view of the bag, 40 the final side fold having been made.

Fig. 5 is a view of the completed bag with a sealing label or stamp in position.

In bags of this character, it is customary to form them of fabric and provide the neck 45 of the bag with strings, which, after the bag is filled, are drawn tightly so as to close the neck of the bag. This practice, which has long been followed, results in bunching the fabric of the neck centrally of the bag, 50 and over this neck the sealing label or revenue stamp passes. With the old arrangement, some difficulty is experienced in applying the sealing label or stamp, and furthermore, it is necessary for the consumer 55 in opening the package to untie the draw

strings, which are usually knotted together, and then loosen the neck so as to open the bag, and as these strings are drawn and knotted very tightly, initial opening of the bag is sometimes difficult.

In the construction devised by me, these difficulties are overcome so that a smooth, flat, well-shaped top is formed, over which the sealing label or stamp may be readily and smoothly applied, and in which the initial opening of the bag is readily accomplished, as the consumer has only to unfold the closure without opening up a bunch or drawn neck. After this initial opening, the bag may be used in the ordinary way and 60 closed by means of the draw strings.

Referring to the drawings by numbers, like numbers indicating like parts in the several views, 10 designates a bag of any suitable material having the open top 11 65 with the draw strings 12 laid in the string pocket formed at the neck of the bag as is customary.

The essential thing in the method of closing and the closure invented by me is the inturning of the drawing strings and the neck of the bag in unpuckered condition, and while this may be accomplished in a varied number of ways, it is preferably done in the manner hereafter set forth.

The initial step in forming the closure is preferably the inturning of the end folds 13 along the dotted lines shown in Fig. 1, the inturned position of these folds 13 being shown in Fig. 2 so that they lie flat against the top of the contents of the package with the draw strings 12 laid flat in the position shown in Fig. 3. The next step in effecting the closure is to inturn the side flap 14 as shown in Fig. 3, the flap 14 folding down 90 flatly over the inturned folds 13 and the draw strings 12.

The next step in the formation of the closure is the inturning of the side fold 15 as shown in Fig. 4, this being folded flat upon 100 the first side fold 13, and giving a comparatively flat, smooth top, as shown.

The flat, smooth surface thus formed may be sealed or secured in any suitable manner, either by pasting the flaps themselves in place, by mechanical fastening means, or, as herein shown, by the use of the sealing label or stamp 16, (Fig. 5) which may be conveniently secured over the top of the bag, the closure described forming 110

a relatively smooth and firm closure to which the stamp will readily adhere, and the ends of the stamp may then be wiped downwardly along the sides of the package, as shown in Fig. 5.

This closure and method of closing gives a package which is of uniform size and shape at its ends, eliminates bunching and compression of the package by the draw strings so that a smooth surface for the sealing stamp or label is provided, and as will be obvious, eliminates all projecting corners or ends as the package is turned out from the packing machine.

15 The consumer has but to break the sealing label or stamp, open all folds, as heretofore described, and the contents of the package are accessible. At the same time all of the advantages of the old packages are retained 20 in so far as the draw strings are concerned, for after the initial opening, the consumer may utilize the draw strings in the usual manner to close the neck of the bag.

It will be understood that variations in 25 the manner of folding and disposing of the various folds and the draw strings may be made in effecting this closure without departing from the spirit of the invention, and, furthermore, while I have shown two 30 draw strings as is customary in this type of container, it is equally applicable to bags in which a single draw string is used.

I claim:—

1. A closure for strung bags having its 35 end folds and draw strings in loose untied condition inturned so as to lie flat upon

the top of the package, its side folds inturned and folded flat upon said end folds and draw strings, and means to secure said inturned and flattened folds in position.

40

2. A closure for strung bags having its end folds and draw strings in loose untied condition inturned so as to lie flat upon the top of the package, its side folds inturned and folded flat upon said end folds and 45 draw strings, and a stamp or label to hold said flattened folds in position.

45

3. A closure for strung bags having its end folds and draw strings in loose untied condition inturned so as to lie flat upon the 50 top of the package, its side folds inturned and folded flat upon said end folds and draw strings, and a revenue stamp to hold the inturned and flattened folds in position.

50

4. A closure for strung bags having opposite folds of its unpuckered top and the draw strings in loose untied condition inturned so as to lie flat upon the top of the package, its other folds inturned and folded 55 flat upon said first-named folds and draw strings, and means to hold the inturned and flattened folds in position.

55

5. A closure for strung bags having the draw strings, in undrawn condition, inturned so as to lie flat upon the top of the 60 package, the folds of the unpuckered top inturned upon said draw strings, and means to hold the inturned and flattened folds in position.

60

65 In testimony whereof I have hereunto set my hand.

PAUL ELLIOTT CREWS.
